UNITED STATES PATENT OFFICE.

BATTESTA CHINI, OF FLUSHING, OHIO.

SWITCH STAND.

Application filed September 17, 1921. Serial No. 501,249.

To all whom it may concern:

Be it known that I, BATTESTA CHINI, a citizen of the United States, residing at Flushing, in the county of Belmont and 5 State of Ohio, have invented certain new and useful Improvements in a Switch Stand; and I do hereby declare the following to be a full, clear, and exact description of the invention, such as will enable others skilled in 10 the art to which it appertains to make and use the same.

The object of the invention is to provide a switch stand or switch operating mechanism whereby the switch rails may readily 15 be moved from open to closed position or the reverse thereof and is held locked in either position against accidental displacement by jarring or vibration, and while capable of movement from one position to the other 20 without the release or specific operation of any particular locking means, can be adjusted only by the exercise of a considerable amount of force by reason of the fact that the holding or retaining element is yield- 25 ingly held in position to lock the switch rail by a relatively heavily tensioned spring; and with this object in view the invention consists in a construction, combination and relation of parts of which preferred embodiments 30 are shown in the accompanying drawings, wherein:

Figure 1 is a general view in plan of a switch mechanism including a stand having a locking means embodying the invention.

35 Figure 2 is a side view of the switch stand.

Figure 3 is an inverted plan view of the stand showing the switch operating and locking means.

40 Figures 4, 5 and 6 are views similar to Figure 3 showing respectively modified forms of the switch operating and locking means.

45 Figure 7 is a side view of the construction illustrated in Figure 6 to show the relation of the hand lever in connection with the switch operating member.

50 Figure 8 is a detail sectional view of a preferred form of bearing for the operating arm of the mechanism on the plane indicated by the line 8—8 of Figure 3.

55 Figure 9 is a detail sectional view of a portion of the base plate at and parallel with the end of the slot in which the hand lever is moved, to show one of the terminal contacts for engagement by the operating member.

The switch stand 10 includes the base 11 and hand lever 12, suitably pivoted as indicated at 13 and having a forked extremity 14 for engagement with the tapered extremity 60 15 of a switch rail operating member 16, consisting in the construction illustrated in Figures 1, 2 and 3, of an angle lever fulcrumed at 17 and having its arm 18 connected by a bolt 19 or the equivalent thereof to a switch 65 bar 20 extending to the switch rail 21.

In this form of the apparatus the arm 18 of the angle or bell crank lever constitutes an element of the means for locking the switch rail in its adjusted position, and in 70 cooperation therewith is a relatively strong contractile spring 22 connected with said arm 18, at a distance from the fulcrum thereof, as to the bolt 19 by which the switch bar is connected therewith, the other end of the 75 spring being so positioned with relation to the limited path of swinging movement of the arm 18, that when the said arm is at the limits of its movement or path, at which the switch rail is respectively in its closed or 80 opened position, the line of strain of the spring 22 is at one side or the other of the plane of the pivot or fulcrum 17 of said bell crank lever and thus serves to hold the said lever in its adjusted positions, with the operating arm thereof, with which engagement is 85 made by the hand lever, in contact with one or the other of the stops 23. In the construction shown in Figure 3 the inner end of the spring, or the end opposite to that which is 90 connected with the arm 18 of the bell crank or oscillatory lever, is attached to a fixed eye or clip 24 and in Figure 3 the terminal and oppositely locking positions of the spring are shown respectively in full and dotted 95 lines to constitute in connection with the arm 18 an eccentric or dead-center lock.

While the parts may be moved from one adjusted position to the other, to correspondingly throw the switch rail, by means of the 100 hand lever, it will be obvious that considerable force must be applied in opposition to the tension of the spring to move the arm 18 from one of its terminal positions to a position in which the spring is in the plane of the fulcrum 17. The further movement of the parts, after the spring reaches a position of alignment is assisted by the spring and the tension of the latter thus serves to hold the parts in the newly adjusted position 105 against movement in the opposite direction.

In the modified form of the mechanism

illustrated in Figure 4 the switch rail operating member 16^a which is adapted for actuation as in the form shown in Figure 3 by means of a suitable hand lever and is fulcrumed at 17^a, with an arm 18^a connected by means of a bolt 19^a with the switch bar 20^a, is provided with a locking means including a contractile spring 22^a cooperating with the arm 18^a and adapted for arrangement upon either side of the plane of the fulcrum 17^a as previously described, but in this form the inner end of the spring is movably mounted by means of a carrier 23^a, taking the place of the eye or staple 23 of the form shown in Figure 3, said carrier being fulcrumed at 24 and being geared at its inner end as shown at 25 to the inner end 26 of the arm 18^a, so that the carrier moves with the arm 18^a in a direction opposite thereto, to cause a more extensive bodily movement of the spring 22^a than is possible with the form shown in Figure 3 for the reason that both ends of said spring are moved transversely with the adjustment of the switch rail, to position the line of its strain or draft upon opposite sides of the plane of the fulcrum 17^a of the locking arm 18^a. In other words in the form shown in Figure 4 both ends of the contractile spring are moved relative to the fulcrum 17^a and as a consequence a greater amplitude of displacement of the line of draft from the plane of the fulcrum 17^a may be secured, to increase, if required the resistance offered by the parts to a change of position in throwing the switch rail and greater security in locking the switch rail in its adjusted position.

In the further modified construction illustrated in Figure 5 the switch rail operating member 16^b, adapted as in the previous form to be operated by suitable hand lever, carries the arm 18^b, the fulcrum being indicated at 17^b, and said arm 18^b being connected as before with the switch bar 20^b with a contractile spring 22^b connected with the arm 18^b near its extremity, but in this instance a movable anchor is provided for the inner end of said spring consisting of a carrier 23^b having a rack 27 with which meshes a gear 25^b in turn meshing with a gear face 26^b concentric with the fulcrum 17^b, so that movement of the switch rail operating member from one position to the other causes a movement of the carrier 23^b in a direction corresponding with the free end of the arm 18^b, to give a considerable amplitude of bodily movement of the spring 22^b to position it, in the adjusted positions of the switch bar, at considerable distances upon opposite sides of the plane of the fulcrum 17^b, for a reason corresponding with that given in regard to the modification shown in Figure 4. A heavier spring may be employed with this construction if desired to

increase the security with which the switch rail is held in its adjusted position or the distance through which the spring passes or the displacement thereof upon either side of the plane of the fulcrum 17^a may be increased, to correspondingly increase the security of the lock. 70

In the modified form shown in Figure 6, the switch rail operating member 16^c consists of a sliding bar actuatable as indicated in Figure 7 by a hand lever 28 having a tapered extremity 29 for engagement with a slot 30, said bar 16^c having racks 26^c for engagement with gears 25^c concentric with the pivotal points 17^c at the inner ends of locking arms 18^c of which the remote ends are connected by a contractile spring 22^c adapted for arrangement upon opposite sides of the plane of the fulcrums 17^c of said arms 18^c to correspond with the open or closed positions of the switch rail, and serving to lock the parts as previously described in the adjusted positions of the switch rail. 75 80 85 90

It will thus be seen that in all the various forms or adaptations of the invention the switch rail operating member is adapted to be locked with the switch rail in its adjusted position, whether open or closed, by means involving an eccentric or dead center lock and including a swinging or pivotal arm or member with which is connected a contractile spring movable with and by the said swinging arm or member to occupy positions respectively at opposite sides of the plane of the fulcrum of the said arm or member, so that the tensile strain of the spring is applied in a direction tending to continue the shifting movement of the rail operating member and thus hold the rail in its adjusted position. 95 100 105

As a means of reducing the frictional resistance offered by the movement of the operating member which in the construction illustrated in Figures 1, 2 and 3 includes the arm 18 carried by the member 16, it is preferred to employ a ball bearing as indicated at 31, wherein the balls are arranged in an annular race or runway between the operating member and the base plate 11, as shown particularly in Figure 8. 110 115

Moreover inasmuch as under some conditions it is desirable to have a visible evidence of the fact that the operating member of the switch mechanism is in one or the other of its adjusted positions, with the switch rail in either the open or closed position, there may as indicated in Figures 1 and 3 be employed in connection therewith an indicator having differently colored electric light units 32 and 33 included in circuits 32^a and 33^a with a battery 34 and the contact 32^b and 33^b arranged in the paths of movement in opposite direction of the tapered extremity 15 of the operating member 16, said contact being insulated as at 35 from the base plate so. 120 125 130

that one or the other of the lighting units is arranged in a closed circuit according to the position of the operating member and thereby disclosed definitely the position of said 5 lever.

Having thus described the invention, what I claim is:—

1. A switch rail operating mechanism comprising a base, a member pivoted to said 10 base, said member having teeth formed concentric with said pivot, a second member pivoted to said base and having gear teeth concentric with its pivot, a contractile spring fastened to the member first named 15 and means whereby when one end of the spring is shifted to a point at one side of the pivot of the member first named, the other end of the spring will also be shifted.

2. A switch rail operating mechanism 20 comprising a base plate having a slot therein and upstanding bearing ears adjacent said slot, an operating handle pivoted to said bearing ears and extending through the slot, arms arranged at an angle to each other 25 and pivoted to said base and disposed at the under side thereof, and operating connections between said arms and said operating handle whereby on movement of the operating handle the arms move simultaneously.

3. A switch rail operating mechanism 30 comprising a base plate having a slot therein and upstanding bearing ears adjacent said slot, an operating handle pivoted to said bearing ears and extending through the 35 slot, arms arranged at an angle to each other and pivoted to said base plate and disposed at the under side thereof, a contractile spring connected to one of said arms adjacent its free end and serving to hold it in a position 40 at either side of its pivot, and operating connections between said arms and said handle whereby on movement of the handle the arms move simultaneously.

4. A switch rail operating mechanism 45 comprising a base plate having a slot therein and upstanding bearing ears adjacent said slot, an operating handle pivoted to said bearing ears and extending through the

slot, a bell crank lever pivoted to said plate and disposed at the under side thereof, a 50 contractile spring connected to one arm of said bell crank lever adjacent its free end and serving to hold the arm in a position at either side of its pivot, and operating connections between the other arm of said bell 55 crank lever and said operating handle whereby on movement of the operating handle the switch rail is moved.

5. A switch rail operating mechanism comprising a base plate having a slot therein and upstanding bearing ears adjacent said slot, an operating handle pivoted to 60 said bearing ears and extending through the slot, a bell crank lever pivoted to said plate and disposed at the under side thereof, and 65 operating connections between one arm of said bell crank lever and the operating handle whereby on movement of the operating handle the bell crank is moved.

6. A switch rail operating mechanism 70 comprising a base, members carried by said base and having gear teeth formed thereon, a contractile spring having one end fastened to one of said members and having its other end fastened to another of said members, 75 and means for causing said members to move in unison and to shift the second end of the spring upon the shifting of the first end.

7. A switch rail operating mechanism 80 comprising a base plate, spaced movable members carried by said base plate and being provided with teeth, a contractile spring having one end secured to each of said members, a member intermediate said members 85 and having teeth meshing with the teeth of the spaced members, and an operating handle to move said members and to thereby cause the shifting of the spring.

In testimony whereof I affix my signature 90 in presence of two witnesses.
